[57] CLAIM

The ornamental design for a miniature lantern, as shown and described.

DESCRIPTION

FIG. 1 is a perspective view, taken from the front, right side, and top of the miniature lantern illustrating our new design, with a support stand shown in a closed position and a light bulb in a closed position;

FIG. 2 is a view similar to that shown in FIG. 1 with the stand shown in an extended position and the light bulb shown in an extended position;

FIG. 3 is a left side elevational view of our design as shown in FIG. 1;

FIG. 4 is a top plan view thereof;

FIG. 5 is a front elevational view thereof;

FIG. 6 is a right side elevational view thereof;

FIG. 7 is a rear elevational view thereof; and,

FIG. 8 is a bottom plan view thereof.
